AUTOMATIC SUPERVISORY EQUIPMENT

James H. Oliver, Philadelphia, Pa., assignor to
General Electric Company, a corporation of
New York

Application August 16, 1929, Serial No. 386,429

15 Claims. (Cl. 177—353)

My invention relates to supervisory control systems and more particularly to novel methods and means whereby a remote apparatus unit, may be selectively controlled and supervised.

5 My invention has for one of its objects to provide a supervisory control system which has the characteristic of great reliability both in its selecting and remote control function and which may be employed to supervise and control important 10 apparatus units of a power distribution system, for example, over lines which may parallel those of the distribution system itself and which are therefore subject to severe inductive disturbances.

In the remote control and supervision of apparatus units over lines of the character indicated 15 the effect upon the control equipment of induced potentials in the line may be reduced by going to the trouble and expense of properly shielding the line conductors thereby to reduce the induced 20 potential itself.

My invention has for one of its objects, however, to provide a system which will operate with great reliability over these lines independently of any shielding of the line conductors, insulating 25 transformers or condensers which may be included in the line, and which further accomplishes this result without recourse to expensive high frequency carrier current equipment.

Another object of my invention is to provide 30 certain novel improvements in the nature of the selecting equipment employed whereby increased reliability in the selecting operation may be had and whereby, due to such faulty operation of the selecting equipment as may occur from time to 35 time, the operation will in practically all cases result in no selection, or whereby the possibility of an incorrect selection of a remote apparatus unit is rendered extremely remote.

A further object of the invention is to provide 40 a novel method of control of remote equipment and means whereby the method may be practiced, including means, whereby, after a remote apparatus unit has been selected, as in response to a predetermined code, it may then be controlled only in response to a fixed additional code. In accordance with this feature of the invention 45 after an apparatus unit has been selected in response to a certain code the apparatus unit, if it be a power switch, for example, will be operated to its closed position and in response to a different code will be operated to its open position. Further in accordance with this feature of my invention I provide means whereby 50 when through the apparatus unit selecting equipment, a particular apparatus unit has been se-

lected it may be successively operated and controlled in response to the additional codes from one position to another, back and forth, as many times as desired without again operating the apparatus unit selecting equipment. A further 60 object of the invention is to provide means whereby, when due to faulty operation of the equipment in response to these additional codes in practically all cases no control operation is effected and whereby the possibility of an incorrect control operation in response to these additional codes is rendered very remote. 65

A further object of the invention is to provide coding means common to all of the remote units supervised whereby after any unit has been selected a persistant indication of the unit selected and the position thereof may be transmitted from the remote station to the dispatcher's station. Another object is to provide means whereby this 70 result is effected without operation of the selected unit and whereby when the unit is operated either automatically or by remote control the indication is altered in accordance with the new position of the unit. 75

A still further object of my invention relates 80 to certain improvements in means for indicating in the dispatcher's station the automatic or accidental operation of remote units and the position thereof.

A further object of the invention is to provide 85 a system in which the equipment provided may be utilized for the remote control and supervision of apparatus units having three or more positions such as rheostats, water gates and the like, and whereby with the addition of a very slight amount 90 of equipment both units having two positions and units having a greater number of positions may be supervised and controlled.

Various other objects of my invention relate to the provision of a system whereby the above results 95 may be accomplished in an economical and practical manner, which employs relatively few relays per unit supervised, and which avoids the use of relays which have a necessarily delicate or critical time adjustment. Another object is to 100 provide a system whereby the desired supervision, selection and control may be effected over a single pair of line conductors such as those which may be found in use in a particular installation, for purposes of telephony. Still other objects of my 105 invention will be apparent from the following description.

The novel features which I believe to be characteristic of my invention are set forth with particularity in the appended claims. My inven- 110

tion itself, however, both as to its organization and method of operation, together with further objects and advantages thereof may best be understood by reference to the following description taken in connection with the accompanying drawings on which Fig. 1 represents a portion of my equipment, Fig. 2 represents the receiving selecting equipment and Fig. 3 represents a number of apparatus units which are to be supervised together with the code transmitting equipment which is employed at the remote station.

Referring to the drawings I have represented at the left-hand portion in Fig. 1 a dispatcher's station, indicated at A. This station is connected by means of a line L with a station B at which the remaining portion of my system is located, this portion of the system comprising the remaining apparatus indicated in Fig. 1, and in Figs. 2 and 3.

I have indicated at t and t' telephone equipment which may also be used over the line L. The equipment is arranged to be cut out of circuit by a key 18 as will later be indicated.

Referring first to Fig. 3 of the drawings I have represented at 1, 2 and 3 a number of power switches which are to be controlled and supervised from the station A. I have also shown in Fig. 3 of the drawings a number of apparatus units represented by elements 4 and 5 which are movable through three or more positions, and which are arranged to be operated from one position to another through local means associated therewith or from the station A, and the position thereof indicated in the dispatcher's station. These elements 4 and 5 may, for example, comprise the movable element of a meter, or the movable armature of a rheostat whereby load control is effected. Similarly these elements may be varied in position in accordance with water level, gate positions and the like, and the positions thereof may be transmitted to the station A to indicate the reading of the meter, the load, water level, or gate position, as the case may be. Associated with each of the apparatus units 1, —5 is a control relay 1', —5'. In the case of the power switches 1, 2, 3 these control relays are arranged to control the operating and trip circuits of the associated switch. In the case of the apparatus units 4 and 5 these relays may be arranged to control the motor circuit whereby the field rheostat is operated, as shown in connection with apparatus unit 4, or any other suitable circuit for controlling the position of the movable element as, for example, a motor circuit for operating a water gate. These relays are preferably of the polarized position type and are operated from a neutral position to either of two other positions in response to current of proper polarity and return to the neutral position when deenergized. For certain applications, however, it is desirable that certain of these relays be of the polarized two-position type which remain, when deenergized, in the position to which it was last operated.

Also associated with each of the apparatus units 1, —5 is an indicating relay 1'', —5''. These relays are normally energized through a circuit which extends from the neutral bus 6 through the right-hand contacts of the individual relays and thence, in the case of the relays associated with the power switches, to either the positive bus 7 or the negative bus 8 as determined by the position of an interlock 9, 10, 11 which is mechanically associated with each of the respective switches. Thus the relays 1'', 2'', 3'' are normally energized in either position of the power switch. The holding

circuit for each of the relays 4'', 5'' is permanently connected to the positive bus 7, thereby to maintain these relays normally energized. In each of these holding circuits between the coil of the corresponding relay and the positive or negative bus, as the case may be, is a resistance such as that shown at 71 in the circuit of relay 2''. The purpose of these resistances will later be indicated.

Associated with and common to all of the apparatus units supervised is a code selector switch 5S and a code transmitter switch 6S. The circuit arrangement is such that upon automatic operation of any apparatus unit 1, 2, 3, the associated indicating relay 1'', 2'', 3'', becomes deenergized and interrupts its holding circuit. In response to this operation the code selector switch will operate from its normal position, which is that shown in the drawings, to a different position, dependent upon the apparatus unit which operated. When this has occurred the code transmitter switch 6S will start to rotate and in so doing, by means of either a high pitch, or low pitch, buzzer indicated at 12 and 13 respectively, in Fig. 1, will transmit to the dispatcher's station a code of impulses indicating the unit which operated. A position responsive relay 14 is provided as shown in Fig. 2 whereby the code will be transmitted by either of the buzzers 12 or 13 dependently upon the position of the apparatus unit. The buzzers 12 and 13 operate to transmit high frequency impulses through a transformer 15, insulating transformer 16', line L, insulating transformer 16 of the station A to any suitable form of indicating device in the dispatcher's station. Preferably this indicating device may take the form of an induction howler or loud speaker indicated at 17 in the station A.

Thus the operator may determine by the code which is received what apparatus unit has operated and by the pitch received from the howler the position to which the unit has operated.

After these indications have been recognized by the operator he may by pressing a reset key 18 in his station interrupt the indication and simultaneously reset the equipment at the remote station to the normal position which is that shown in the drawings leaving the apparatus unit in its operated position.

If it be assumed that the operator desires to ascertain the position of a certain remote switch or other apparatus unit, without operating it, he will dial a code corresponding to that unit upon a suitable code transmitting device which is indicated at 20 at the station A thereby causing a code of high frequency impulses to be transmitted to the remote station. Through a selective mechanism indicated in Fig. 2 of the drawings the indicating relay corresponding to the unit, the code number of which has been dialed will be deenergized. Deenergization of this relay will then cause operation of the code selector and code transmitting switches to transmit to the dispatcher's station a code corresponding to the unit selected if the unit be a power switch, and having a pitch indicating the position of the selected unit. If the selected unit be one having three or more positions the code transmitted will correspond to the position of the unit.

In the case of the two position units such as the switches 1, 2 and 3 the code transmitted back to the dispatcher's station may preferably be the same as the code which was transmitted

from the dispatcher's station to the remote station to effect the desired indication. In the case of the units having three or more positions, the code transmitted back to the dispatcher's station is preferably one having a number of impulses depending upon the position of the selected unit.

Having selected a desired unit by means of the selector equipment indicated at TS, 1S, 2S and 3S in Fig. 2 of the drawings, if it be assumed that the operator desires to change the position of the selected unit, he will then dial a further code to which a position selector indicated at 4S in Fig. 2 of the drawings responds. This selector operates through relays 19 and 19' in Fig. 1 to supply current of desired polarity to the control relay of the selected unit, thereby to operate that relay from either position to the other to effect the desired change in position of the selected unit. In the case of the two-position units such as 1, 2, 3, this change in position will cause operation of the position transmitting relay 14, which, in turn, immediately changes the tone of the code transmitted to conform with the position of the switch. In the case of the units 4, 5 the change in position will change the code transmitted.

The selecting equipment indicated in Fig. 2 is of considerable importance in connection with the reliability of operation of my invention. The equipment, as has been previously indicated, comprises primarily the selector switches TS, 1S, 2S, 3S and 4S, together with a group of relays, of which 39 and 82 are indicated in the drawings. These selector switches are of well known construction comprising a plurality of wipers which are actuated over a bank of contacts in a step-by-step manner by means of a suitable motor magnet through a ratchet and pawl arrangement. If desired switches of the type shown in United States Patent No. 1,472,465, Oscar F. Forsberg et al., issued October 30, 1923, may be employed. It may be mentioned here that the switches 5S and 6S of Fig. 3 are of the same construction. While any desired number of contacts may be employed in the banks of the different switches, for most purposes, the switches TS, 1S, 3S, 4S preferably include 11 contacts on each bank, whereas the switches 2S, 5S and 6S include twenty-five contacts in each bank.

For convenience in description, I choose to term the switches 1S, 2S and 3S collectively either with or without the switch TS, the "apparatus units selector" the switch TS the "transfer selector" and the switch 4S the "position selector", corresponding legends being applied to the drawings.

To obtain the desired degree of reliability the code corresponding to each apparatus unit preferably includes three or more groups of impulses, the apparatus unit selector, including, in addition to the transfer selector, a selector switch corresponding to each group of impulses in the different codes. The function of the transfer selector is to supply each group of impulses received in any code to the motor magnet of the appropriate selector switch and at the end of the code to connect the position selector to respond to any further code which may be received. In this manner the selector switches 1S, 2S, and 3S are respectively positioned in response to its appropriate group of impulses and serve thereby to select a particular apparatus unit. The position of the selected unit may then

be controlled by further codes to which the position selector responds without further operation of the apparatus unit selector mechanism.

The advantages of this method of selection will later be pointed out.

Having now briefly indicated the character of the equipment to be disclosed its more detailed structure and operation will now be more fully explained.

Located at the station A is a high frequency code transmitting device comprising a dialing device 20 and an induction coil 22, the induction coil 22 having a primary winding and a secondary winding. The primary winding of the coil 22 is connected in circuit with a pair of interrupter contacts 22' on the induction coil, dialing contacts 23, and battery 24. The secondary winding of the induction coil is connected in circuit with one winding of the insulating transformer 16 at the dispatcher's station through a pair of normally open contacts 25 which are controlled by the dial 20. This winding of the transformer 16 is also normally connected in circuit with the induction howler 17 through normally closed contacts 26 controlled by the dial 20.

The dialing device 20 is of a well-known construction, used in telephone practice, and is so arranged that when operated from its normal position, it opens the contacts 26 thereby interrupting the circuit of the induction howler and closing contacts 25 thereby completing the circuit of the secondary winding of the induction coil. When released the dial returns to its normal position under influence of a suitable biasing spring, or other mechanism, and periodically closes the contacts 23 a number of times depending upon the extent of movement of the dial from its normal position. After it has returned to its normal position it will again open the contacts 25 and close the contacts 26, thereby again connecting the howler in circuit with the transformer 16. Thus a code of high frequency impulses will be transmitted over the line L.

At the remote station the relay 27 is connected across one of the windings of the transformer 16' such that it responds to the high frequency impulses received from the dispatcher's station. In circuit with this relay is a filter comprising an inductance F and a condenser F' for preventing low frequency and direct current impulses on the line from operating the relay 27.

Let us assume that the operator dials the number corresponding to the switch 2 at the remote station thereby to ascertain the position of that switch. The code number of this switch, as indicated on the drawings, is 2-3-9. The operator will then dial this number upon his dial 20 in the usual manner, thereby sending three groups of impulses having 2, 3, and 9 impulses respectively, the groups of impulses being separated by a time interval greater than the time interval between impulses of any group.

Relay 27 at the remote station responds to these high frequency impulses thereby closing an obvious circuit between the positive bus 8', 140 which is connected to bus 7 and the negative bus 8 through the actuating winding of relay 28. Relay 28 thus follows the operation of relay 27, and energizes relay 29 through an obvious circuit between the positive bus 7 and the negative bus 8. Upon each operation of relay 29 a circuit is completed which extends from the positive bus 7 through the right-hand contacts of relay 29, conductor 30, wiper and normal contact of the bank TS-2 of selector switch TS and motor

magnet 31 of the switch 1S to the negative bus 8. The motor magnet 31 is thus energized twice in response to the first group of impulses of the code and, upon each deenergization thereof selector switch 1S is moved from the normal position to its second off-normal position.

It will be seen that relay 32 is energized upon each energization of relay 29 through an obvious circuit. This relay is slow to release, and its armatures are not operated between the impulses of the respective groups. However, the time delay characteristic of this relay is such that the armatures of this relay are operated to the normal position shown in the drawing during the time interval between groups of impulses thereby completing a circuit which extends from the negative bus 8 through the motor magnet 33 of the transfer switch TS, interrupter contacts thereof, conductor 135 right-hand contacts of relay 32, contacts 34' of relay 34, conductor 35, wiper and normal contact of bank TS-3, wiper of bank 1S-1 in its second position and conductor 85 to the positive bus 7. Thus motor magnet 33 is energized and in operating interrupts its own circuit thereby stopping the transfer switch on to its first off-normal contact.

When the second group of impulses is received motor magnet 33 will be operated through a circuit extending from the positive bus 7 through the right-hand contacts of relay 29, wiper and first contact of bank TS-2, and motor magnet 36 to the negative bus 8. Thus the motor magnet 36 will operate the selector switch 2S to its third off-normal contact, since there are three impulses in the second group of the code transmitted. At the end of the group, relay 32 again becomes deenergized and in operating to its normal position again energizes motor magnet 33 of the transfer selector, the circuit now extending from the negative bus 8 through the motor magnet 33 and its interrupter contacts, conductor 135 right-hand contacts of the relay 32, contacts 34' of relay 34, conductor 35, wiper and first contact of bank TS-3 wiper and third contact of bank 2S-1 and conductor 85 to the positive bus 7. Motor magnet 33 will then operate the transfer selector to its second off-normal contact.

In response to the next group of impulses motor magnet 37 will be energized, this circuit extending from the positive bus 7 through the right-hand contacts of relay 29, conductor 30, wiper and second contact of bank TS-2, and motor magnet 37 to the negative bus 8. Since there are 9 impulses in the third group, selector 3S will be operated to its ninth position. At the end of this group of impulses relay 32 is again deenergized and advances the transfer switch to its third position, the circuit extending from the negative bus 8 through the motor magnet 33 and its interrupter contacts, conductor 135, right-hand contacts of relay 32, contacts 34' of relay 34, conductor 35, wiper and second contact of bank TS-3, wiper and ninth contact of bank 3S-1 and conductor 85 to the positive bus 7.

It will thus be seen that in response to receipt of the code the switch 1S is operated a number of times depending upon the number of impulses in the first group of the code, after which the transfer selector is operated to interrupt the circuit of the motor magnet of the switch 1S and to connect in circuit the motor magnet of the switch 2S. Switch 2S then responds to the second group of the code after which the transfer selector is again operated to interrupt the circuit of its motor magnet and to connect in circuit the motor

magnet of the switch 3S. Switch 3S then responds to the third group of the code after which the transfer selector is again operated to interrupt the circuit of its motor magnet and to connect in circuit, as will later be indicated, the motor magnet of the switch 4S. This completes the apparatus unit selecting operation.

The circuits are so arranged that an apparatus unit is selected in response to the relative position of the different switches in the apparatus unit selector.

Thus in the case assumed with the selector TS in engagement with its third off-normal contact, selector 1S in engagement with its second off-normal contact, selector 2S in engagement with its third off-normal contact and selector 3S in engagement with its ninth off-normal contact, a circuit will be completed which extends from the positive bus 7 through conductor 32, wiper and second contact of the bank 1S-2 winding of relay 39, conductor 40, wiper and third contact of the bank 2S-2, wiper and ninth contact of the bank 3S-2 conductor 41, and wiper and third contact of bank TS-4 back to the negative bus 8.

The groups of relays 39, 82 I choose for convenience to term "short circuiting relays" for a reason presently to be indicated. Short circuiting relay 39 is now energized and by means of its left-hand contacts completes a short circuit connection which extends from the neutral bus 6 through the left-hand contacts of relay 42, left-hand contacts of relay 39, wiper and third contact of the bank 2S-4, conductor 43, winding of relay 2'' and its right-hand armature back to the neutral conductor 6. This connection short circuits the winding of relay 2'' which then deenergizes and at its right-hand contacts opens its holding circuit, which has been previously traced.

At its left-hand contacts relay 2'' completes a circuit which extends from the positive bus 7 through conductor 44, left-hand contacts of relay 2'', conductor 45, and winding of relay 46 to the negative bus. At the same time at its middle contacts relay 2'' interrupts a connection from the positive bus through conductor 44 to the eighth contact on bank 5S-5 for a purpose later to be indicated.

Energization of relay 46 completes a circuit which extends from positive bus 7 through the left-hand contacts of relay 43, winding of relay 47, conductor 48, contacts 49 on relay 50 of Fig. 1, conductor 48', interrupter contacts, and motor magnet 52 of the switch 5S to the negative bus 8'. Relay 47 does not energize in this circuit for the reason that it is short circuited through the middle contacts of relay 46, conductor 53, normal contact and wiper of bank 5S-5 back to conductor 48. Motor magnet 52, however, energizes and at its interrupter contacts deenergizes itself, advancing switch 5S to its first off-normal contact. Since the first off-normal contact of the bank 5S-5 is connected to positive through the middle contacts of relay 1'' and each successive contact of the bank 5S-5 is similarly connected through contacts on similar relays, not shown, corresponding to other switches which are supervised by the positive bus the motor magnet will again energize upon each successive step of the switch until the switch reaches its eighth contact.

As was previously indicated, the eighth contact is disconnected from the positive bus by operation of the middle contacts of relay 2'' and, accordingly, in this position operation of the switch 5S will be interrupted. The short circuit about the

winding of relay 47 is now removed, and this relay energizes completing a circuit which extends from the negative bus 8 through the left-hand contacts of relay 47, conductor 54, normal contact and 5 wiper of the bank 6S—4, conductor 65, interrupter contacts on motor magnet 66, conductor 67, winding of relay 68 and conductor 38 to the positive bus 7. Relay 68 then energizes and through its right-hand contacts completes an 10 obvious circuit for relay 69. Relay 69 then energizes and completes a circuit which extends from the positive bus 7 through conductor 38, contacts on relay 69, conductor 70 and motor magnet 66 of the switch 6S to the negative bus 8'. The 15 motor magnet 66 energizes and in operating its interrupter contacts deenergizes the previously traced circuit for relay 68. Relay 68 then deenergizes relay 69 which in turn deenergizes motor magnet 66. Upon closing its interrupter contacts 20 the motor magnet 66 again energizes relay 68, this cycle of operation repeating itself, and the switch 6S advancing one step upon each deenergization of the motor magnet 66.

Thus, in response to operation of any of the indicating relays the selector switch 5S operates over its contacts to a position corresponding to the particular indicating relay operated. The switch 6S, which I choose to term the code transmitting switch, then continuously rotates and transmits a 25 code to the dispatcher's station corresponding to the position to which the switch 5S, which I choose to call a code selector has operated, this position corresponding to the apparatus unit selected. Thus, in the case assumed, as will be presently indicated, the code transmitted to the dispatcher's station will be 2—3—9. This code will be transmitted in high frequency impulses produced by one or the other of the buzzers 12 or 13, depending upon the position of the apparatus unit selected, the buzzer being operated under control 40 of the code transmitting switch 6S and the code selector switch 5S.

To alternately connect the buzzers 12 and 13 in circuit, depending upon the position of the selected apparatus unit, a code transmitting relay 45 14 is provided. This relay is common to all the apparatus units and is connected in circuit with the interlocking contacts of the selected unit by means of the bank 5S—1. Thus the circuit for the relay 14 extends from positive bus 7 through conductor 38, winding of relay 14, conductor 94, wiper 5S—1 on its eighth contact, resistance 71, and interlock switch 10, in its lower position to the positive bus 7. Thus both terminals of the relay 14 are connected to the positive bus, and the relay is thus short circuited and deenergized. Its right-hand contacts are thus separated thereby interrupting a circuit extending through conductor 72 to the high pitch buzzer 12. The left-hand contacts of relay 14 are closed and complete a circuit which extends from the positive bus 7 through the right-hand contacts of relay 47 which are now closed, contacts of relay 73, left-hand contacts of relay 68, left-hand contacts of 50 relay 14, conductor 75, low pitch buzzer 13, primary winding of output transformer 15 back to the negative bus 8.

As has previously been indicated relays 68 and 69 operate alternately in a cycle with the motor magnet 66 to rotate the switch 6S. These relays are slow to release and operate in a proper period determined by the time-delay means associated therewith, and which are indicated in the drawings, to rotate the switch 6S at a speed which permits ready reception of the code.

It will be seen that the above circuit for the low pitch buzzer 13 is completed upon each step of the selector switch, i. e. on each energization of relay 68, provided that the contacts of relay 73 are closed. In order to interrupt the operation of buzzer 13 in accordance with a desired code, this relay 73 is provided. This relay is connected in a circuit which extends from the negative bus 8' through conductor 76, winding of relay 73 to conductor 77, and thence intermittently through banks 6S—1, 5S—3 and 5S—4 in a manner presently to be indicated, to conductor 78, and the left-hand contacts of relay 140 to the positive bus 7. Thus, whenever the above traced circuit is completed between the conductors 77 and 78, the relay 73 will be energized and the operation of the buzzer will be interrupted.

It may be well at this point to indicate the nature and operation of the buzzers 13 and 12. These buzzers each comprise a magnet having an armature and a cooperating contact whereby when the magnet is energized the contacts close and short circuit the winding of the magnet. These windings are connected in series with the primary winding of the output transformer 15 such that when the magnet is short circuited the current through the primary winding of the transformer is increased until the contacts separate. The winding of the magnet is then inserted in the circuit causing the current in the primary winding of transformer 15 to reduce until the contacts of the buzzer again close, this operation continuing and high frequency currents being produced in the circuit of the secondary winding of the transformer 15 and condenser 15' having a pitch determined in accordance with the structure, as for example the length of the armature, of the buzzer. These high frequency currents are supplied through the transformer 16' line L, and transformer 16, to the induction 105 howler 17 at the dispatcher's station.

The above indicated circuit for relay 73 will be completed between conductors 77 and 78 in the case assumed, when the switch 6S is on its normal position through wiper 6S—1 and conductor 79. The circuit will then be interrupted until the wiper of 6S—1 reaches its third off-normal contact, at which time the circuit will be completed through said third off-normal contact, conductor 80, and the 8th contact of wiper 110 5S—4. The circuit will again be interrupted when the wiper 6S—1 leaves its third contact and until it engages contact 7 at which point the circuit is completed through said seventh contact, conductor 81, and the eighth contact and wiper of 115 bank 5S—3. The circuit will then be interrupted at 6S—1 until wiper 6S—1 engages its seventeenth contact where it will again be completed through contacts 17 to 24, which are strapped together, of wiper 6S—1 and conductor 120 79. Thus relay 73 will be energized when the wiper of bank 6S—1 is on its zero contact, third, seventh and seventeenth to twenty-fourth contact, and the operation of buzzer 13 will be interrupted in these positions of the switch 6S. The code 125 transmitted will then be 2—3—9, this code being the code transmitted from the dispatcher's station, and which corresponds to the apparatus unit selected.

The operator is now informed by the code received that the transmitted code has been properly received at the remote station, and that the apparatus unit selector has functioned to select the correct apparatus unit. He is also informed by the pitch of the received code as to the posi- 145 150

tion which the selected apparatus unit occupies. It will now be understood that had the code transmitted by the dispatcher consisted of 2-10-2 rather than 2-3-9 the switch 1S 5 would engage its second contact, the switch 2S its tenth contact and the switch 3S its second contact. Relay 39 would likewise, have been energized but the indicating relay 1'' would have been short circuited and deenergized. Deenergization 10 of relay 1'' removes positive potential from the first off-normal contact of bank 5S-5 and, accordingly, after operation of relay 46, switch 5S would have operated to its first off-normal contact. The code transmitted would then have 15 been 2-10-2 as will be obvious from the description already presented.

Had the code transmitted by the dispatcher been 3-9-2 the switch 1S would engage its third contact, the switch 2S its ninth contact, 20 and the switch 3S its second contact. Relay 82 would have been energized rather than relay 39, and this relay would have operated to short circuit the winding of relay 3'' through a circuit extending from the neutral bus 6 through the 25 left-hand contacts of relay 42, left-hand contacts of relay 82, ninth contact of wiper of bank 2S-5, conductor 83, conductor 83 through the winding and right-hand armature of relay 3'' to the neutral bus 6. Thus relay 3'' would have 30 been deenergized and have operated through the relays 46, 47 and selectors 5S and 6S to transmit the received code back to the dispatcher's station in a pitch corresponding to the position of the associated apparatus unit 3.

35 While in the drawings only two short circuiting relays 39, 82 are indicated, it will be apparent that a greater number of these relays may be employed dependently upon the number of integers in the first digit which it is desired to use 40 in the codes corresponding to the different apparatus units. It will be seen that one terminal of the windings of each of these relays is connected to a contact in the bank 1S-2 such that the relay operated is dependent upon the position 45 of the first selector switch 1S. The circuits of these relays also extend through each of the other switches TS, 2S and 3S such that these relays will not be energized unless the different 50 switches are in engagement with their proper contacts. Similarly the connections of the contacts on these relays 39, 82 whereby the indicating relays are short circuited extend through wiper and contacts on the switch 2S such that the relay short circuited is dependent upon the position 55 of this switch. In the same way the control relays 1', 2', 3', 4', 5' are all connected to individual contacts on the switch 3S and extend through contacts of relay 39 or 82.

60 In the use of the codes employed it is preferable that the total number of impulses in the different codes, corresponding to each of the different units supervised, should be equal for all codes and that each code should comprise three, or if more selector switches are employed, a correspondingly greater number of groups of impulses. In this way great reliability of the equipment is accomplished, and the possibility of the selection of an incorrect apparatus unit is rendered remote. In fact the circuits of relays 39 and 42 are so arranged that the addition, or omission, of an impulse in any group of any code will result in neither of these relays being energized and therefore the operation of the code selector 5S and the code transmitter 6S is not effected to 75 transmit a code to the dispatcher. Since the dis-

patcher receives no signal after sending out a code of impulses, he knows that no selection has been made by the impulses transmitted from the dispatcher's station. In this way great security is had against selection of an incorrect unit either due to surges in the line L or due to faulty contacts on any of the relays or on the dialing device. 80

Having determined by the code received that the proper apparatus unit 2 has been selected, let us assume that the operator desires to operate this unit, comprising a circuit breaker, from its open position, to its closed position. To accomplish this the operator will dial an additional code of five impulses. Relays 27, 28, 29 respond to these impulses, the relay 29 completing a circuit which extends from positive bus 7 through the right-hand contacts thereof, conductor 30, wiper and third contact of the bank TS-2 and motor magnet 84 of the position selector 4S to the negative bus 8'. 85 90

Since the circuit of the motor magnet 33 of the transfer selector is now interrupted at the wiper of bank TS-3 on the third contact, this switch will not be actuated when the relay 32 becomes deenergized at the end of this additional code, but will remain in the position which it occupied at the end of the apparatus unit selecting operation. The position selector 4S will be operated in response to this additional code to 105 its fifth contact thereby closing a circuit which extends from the positive bus 7 through conductors 85, 51, right-hand contacts of relay 100, left-hand contacts of relay 32, conductor 26, wiper and fifth contact of bank 4S-4, conductor 110 87, winding of relay 19', left-hand contacts of relay 19 and right-hand contacts of relay 88 to the negative bus 8'. Relay 19' will thus be energized thereby completing a circuit which extends from the negative bus 8' through contacts 89 on 115 relay 19', conductor 108, left-hand contacts of relay 90, conductor 91, middle contacts on relay 39, wiper 3S-4 on its ninth contact, conductor 92, polarized control relay 2', conductor 93, right-hand outer contacts on relay 19' and conductor 120 95 to the positive bus 7. The polarity of current flowing in this circuit will be such as to operate the relay 2' to close the switch 2. 125

When the switch 2 is operated to its upper position the short circuit around the relay 14 is removed and this relay becomes energized through the previously traced circuit extending from the positive bus 7 through conductor 38, winding of relay 14, conductor 94, wiper and eighth contact of the bank 5S-1, resistance 71 and switch 10 130 in its upper position to the negative bus 8. Relay 14 will then be energized thereby interrupting the circuit of the low pitch buzzer 13 and substituting in circuit the high pitch buzzer 12. Thus the operator is informed that the position of the 135 switch is changed. If the switch now changes position automatically it will be seen that the pitch of the code will at once be changed.

The code transmitting switch 6S of course continues to revolve persistently transmitting the 140 received code indicating the selected switch and the position which it occupies.

When relay 19' operates it completes a holding circuit for itself which extends from the negative bus 8' through the right-hand contacts of 145 relay 88, left-hand contacts of relay 19, winding of relay 19', contacts 96 on relay 19', conductor 97, contacts 3 to 10 and wiper of bank 4S-3, and conductor 85, to positive bus 7. Since relay 19' is of the slug type, slow releasing relay, it will 150

remain energized until the position selector 4S has reached its normal position. Relay 19' also completes a circuit which extends from the positive bus 7 through conductor 85, conductor 95, 5 contacts 99 on relay 19' and winding of relay 100 to the negative side of the battery. At the same time relay 19' by its left-hand contacts interrupts the circuit of relay 19 to prevent any possibility of these relays becoming energized at the 10 same time.

Upon operating relay 100 completes a holding circuit for itself which extends from the negative bus 8' through the winding of relay 100, left-hand contacts thereof, conductor 101 and bank 15 4S-2 and its associated wiper to the positive bus 7. At the same time by means of its right-hand contacts it interrupts the original energizing circuit for relay 19'. By means of its middle contacts it completes a circuit for the motor magnet 20 of position selector 4S, this circuit extending from the negative bus 8' through the winding of motor magnet 84 and its interrupter contacts, conductor 102, middle contacts of relay 100, conductor 103, bank 4S-1 all of the off normal 25 contacts of which are strapped together, and associated wiper to the positive bus 7. The motor magnet 84 then operates as a buzzer to restore the switch 4S to its initial position where it is in readiness for the next operation relays 19' and 30 100 becoming deenergized when the position selector reaches the normal position.

If the operator now desires to operate the circuit breaker 2 to its open position, he will dial an additional code of three impulses. Relay 29 responding to these impulses will correspondingly 35 energize the motor magnet 84 through the previously traced circuit thereby advancing the position selector 4S to its third contact. In this position a circuit is completed which extends from the negative bus 8' through the right-hand contacts 40 of relay 88, left-hand contacts of relay 19' which are now closed, winding of relay 19, conductor 104, third contact and wiper of the bank 4S-4, conductor 86, left-hand contacts of relay 32, 45 right-hand contacts of relay 100, which are now closed, and conductors 51 and 85 to positive bus 7. Upon energizing, relay 19 completes a holding circuit for itself which extends from the negative bus 8' through the right-hand contacts of relay 50 88, left-hand contacts of relay 19', coil of relay 19, contacts 195 of the relay 19, conductor 97, contacts 3 to 10 and wiper of the bank 4S-3 and conductor 85 to the positive bus 7. The relay 19 similarly with relay 19' is slow to release and, 55 hence, remains energized until the switch 4S reaches its normal contact when it becomes deenergized. At the same time, by closing its contacts 107, it connects conductor 106 to the positive battery through conductors 51 and 85, and 60 by means of its right-hand outer contacts, it connects the conductor 93 to the negative bus 8. In so doing it reverses the polarity of current flowing in the winding of polarized control relay 2' and thereby trips the circuit breaker 2 to its open 65 position. The position transmitting relay 14 then becomes deenergized and again inserts the low pitch buzzer 13 in the circuit to change the pitch of the transmitted impulses.

It will thus be seen that the two outer right-hand contacts of relays 19 and 19' operate as a reversing switch for controlling the polarity of current in the circuit of the control relays 1', 2',-5', associated with the selected unit. Upon operation of the position selector to the fifth contact 75 relay 19' becomes energized supplying poten-

tial of one polarity to the selected control relay and when the position selector is operated to its third contact relay 19 becomes energized to supply potential of the opposite polarity to the selected control relay.

Upon operating by means of its contacts 108, relay 19 completes a circuit from the negative bus 8' through the winding of relay 100, conductors 51 and 85 to the positive bus 7. Relay 100 then energizes and, by means of its left-hand contacts, completes a holding circuit for itself which extends through its left-hand contacts, conductor 101, contact and bank of wiper 4S-2, conductor 85, to the positive bus 7. At its right-hand contact it interrupts the original energizing circuit for relay 19. At its middle contacts it again completes the buzzer circuit for the motor magnet 84 of the position selector, this circuit extending, as previously indicated, through conductors 102 and 103 and the bank 4S-1 and wiper of the position selector to the positive bus 7 and negative bus 8'. Motor magnet 84 then operates the position selector to the normal position where its buzzer circuit is interrupted at the normal contact of bank 4S-1. Similarly in this position the holding circuit of relay 100 is interrupted at the normal contact of bank 4S-2 and the holding circuit of relay 19 is interrupted at the normal contact of bank 4S-3 thereby restoring these relays to their normal positions.

It will be seen that all of the off normal contacts in bank 4S-4 with the exception of contacts the third and fifth are connected together. The purpose of this is to establish the buzzer circuit for motor magnet 84 in case the switch 4S stops on any contact other than 3 or 5. This is brought about through operation of slow releasing relay 88 which becomes energized, when this contingency occurs, through a circuit extending from negative bus 8', through relay 88, conductor 88', contacts and wiper of bank 4S-4, conductor 86, left-hand contacts of relay 32, right-hand contacts of relay 100 and conductors 51 and 85 to the positive bus 7. The relay 88 then operates and at its right-hand contacts interrupts the circuit of the windings of relays 19 and 19'. At its left-hand contacts it completes an obvious circuit for relay 100. Relay 100 then operates and at its middle contacts completes the above traced buzzer circuit of motor magnet 84. The time of drop out of relay 88 is such that the motor magnet operates the switch 4S over the third and fifth contacts without interruption. The switch 4S now returns rapidly to zero when it stops due to interruption of the buzzer circuit of the normal contact of bank 4S-1. Relays 88 and 100 now release.

It will thus be seen that after a particular apparatus unit has been selected the operation of the selected unit can be effected only in response to a fixed predetermined code. In this way any accidental operation of the selected unit in response to a surge upon the line L after an apparatus unit has been selected and before the position changing code is transmitted, for example, is prevented. Also, in case of failure of the equipment resulting in the selector 4S failing to operate to the proper contact, either by missing or advancing a step, or more, for any reason, as due to a surge upon the line, or a faulty contact, no operation will result, the position selector immediately returning to its initial position in readiness for a further operation by the dispatcher. It will further be seen that after the apparatus unit has been selected it may be operated back

and forth as many times as desired without changing the position of the apparatus unit selecting mechanism, only one apparatus unit selecting operation being necessary to effect any desired 5 number of control operations of the selected unit.

After an apparatus unit has been selected and the indication of the position thereof received, the operator may, if he desires, then restore all the equipment to the initial position without operating the selected unit. This is effected by operating a reset key 18 at the dispatcher's station from its normal position to its right-hand position. Similarly this may be effected at any other time in the operation of the equipment, either 10 before or after a remote control operation has been effected, or at a time when the selectors of the position selector are in such position, due to incorrect operation, that no unit is selected.

Resetting of the equipment is brought about 20 as follows:—When the reset key 18 is pressed to its right-hand position a direct current impulse is produced from battery 109 in the primary winding of the transformer 16 thereby producing a direct current impulse in the output winding 25 of the transformer 16' at the remote station. The reset relay 110 at the remote station responds to this impulse. This relay has two windings, the left-hand winding of which is connected to the transformer 16' and the right-hand 30 winding of which constitutes a holding winding which is connected in a circuit extending from the positive bus 7 through the right-hand contact of relay 50, and right-hand winding of relay 110 to the negative bus 8'. The current flowing 35 in the right-hand winding of relay 110 is not sufficient to operate the relay although, after the relay has been operated by its left-hand winding, it will be retained in its operated condition by this winding after the operating impulse 40 in the left-hand winding has ceased.

Upon operating relay 110 completes an obvious circuit for relay 50. Relay 50 operates and by means of its contacts 111 completes an obvious circuit for relay 90. It also interrupts the holding circuit of relay 110 at its right-hand contacts which relay drops out. Relay 90 then operates and by means of its contacts 112 completes a holding circuit for itself around the contacts 111 through a circuit which extends from the positive bus 7 through the contacts 112, right-hand contacts of relay 113, which are now closed and winding of relay 90 to the negative bus 8'. Relay 113, it will be seen, is energized whenever any of the switches TS, 1S, 3S and 4S is in engagement with an off-normal contact, its circuit extending directly from the negative bus 8' through conductor 114, interrupter contacts on all the said switches, connected in parallel to the positive bus 7. These interrupter contacts may be 50 in the form of a wiper which engages a continuous conducting bar in any off-normal position, or a bank of contacts which are strapped together, or any other contacting means mechanically associated with the respective switch in a manner such that the circuit is closed therethrough whenever the switch occupies an off-normal position.

When during the selecting operation relay 46 of Fig. 2, operated, it by means of its right-hand contacts, completed a circuit which extends from the negative bus 8 through relay 42, right-hand contacts of relay 46, and contacts on one of the short-circuiting relays 39, 32; 39 in the case assumed, to the positive bus 7. Relay 42, when 70 energized, interrupts the short circuit across the

winding of the selected indicating relay. This leaves the selected relay in condition to be re-energized during the resetting operation.

This function is accomplished by relay 50 when energized, the resetting circuit extending from the neutral bus 6 through contacts 115 of relay 50, conductor 116, wiper 5S—2, in engagement with its eighth contact, winding of relay 2'', and switch 10 in its lower position, in the case assumed, to the positive bus 7. Had the switch 2 been in its upper position this circuit would have been completed to the negative bus 8. In either case the relay 2'' is energized and, upon operating, completes its holding circuit through its right-hand contacts. 80 85 90

It will be seen that by means of the bank 5S—2 this resetting circuit for the indicating relays is selectively connected to the relay associated with the selected apparatus unit.

Energization of relay 2'' deenergizes relay 46 and, at the same time, through its middle contacts supplies positive potential to the eighth contact of the bank 5S—5. Deenergization of relay 46 interrupts the supply of positive potential to the normal contact of bank 5S—5. Since 100 relay 50 is energized and its contacts 49 open, the circuit of the motor magnet and interrupter contacts of switch 5S, which extends from the wiper 5S—5 through conductor 48, contacts 49 and conductor 48', to the motor magnet and thence 105 to the negative bus 8', will remain deenergized and the switch 5S will remain on its eighth contact until relay 50 again deenergizes.

As was previously stated relay 50 by its contacts 111 energizes relay 90 which completes a holding circuit for itself around the contacts 111 of relay 50. Contacts 117 of relay 90 complete an obvious circuit for relay 34. Relay 34 operates and by means of its left-hand contacts 115 interrupts the holding circuit of relay 50. Since the original energizing circuit of relay 50 was interrupted when the reset relay 110 released, relay 50 will now be deenergized. Relay 50 now closes its contacts 49 thereby establishing the buzzer circuit through motor magnet 52 of selector switch 5S and contacts of the bank 5S—5 of that switch. The switch 5S will then return to its normal position where the circuit is interrupted at the middle contacts of relay 46. In this position of switch 5S relay 118 will be energized for a purpose later to be indicated, through a circuit extending from the negative bus 8' through conductor 76, relay 118, conductor 119, normal contact of bank 5S—4, conductor 78, and left-hand contacts of relay 140 to the positive bus 7. 110 120 125 130

Deenergization of relay 47, in response to de-energization of relay 46 interrupts the supply of negative potential through its left-hand contacts and conductor 54 to the normal contact of the bank 6S—4. Switch 6S will then operate 125 around to the normal position where relay 68, and hence, relay 69 and motor magnet 68 will become deenergized and operation will cease. This interrupts the transmission of the code to the dispatcher's station. 130

When switch 6S reaches its normal position relay 120 will be energized also for a purpose later to be indicated through a circuit extending from the negative bus 8', conductor 76, relay 120, conductor 121, wiper and normal contact of the bank 6S—3 and conductor 122 to the positive bus 7. 140 145

Relays 90 and 34 which are now energized, and which have established holding circuits for themselves reset the balance of the equipment, as 150

follows:—By means of contacts 122 on relay 90 a circuit is completed which extends from the positive bus 7 through conductor 85, wiper and contacts of the bank 1S—1, conductor 123, contacts 122 on relay 90; conductor 124, and interrupter contacts, and motor magnet 31 of selector switch 1S to the negative bus 8. This establishes a buzzer circuit for the motor magnet 31 which then serves to operate the switch 1S to its normal position where the buzzer circuit is interrupted at the wiper of bank 1S—1. Contacts 125 of the relay 90 complete a similar circuit for the switch 2S, this circuit extending from the positive bus at conductor 85, through the wiper 2S—1, conductor 126, contacts 125, conductor 127, and interrupter contacts and motor magnet 36 of the switch 2S to the negative bus 8. The motor magnet now operates the switch 2S to its normal position where the circuit is interrupted at the wiper of bank 2S—1. The outer right-hand contacts of relay 90 also complete a similar circuit for the switch 3S, this circuit extending from the positive bus at conductor 85 through the wiper and bank 3S—1, conductor 128, outer right-hand contacts of relay 90, conductor 129, interrupter contacts and motor magnet 37 of the switch 3S to the negative bus. Thus all of these switches are now operated to the normal position.

30 The transfer selector is reset as follows: Upon operation of relay 34 a circuit is completed from the positive bus at the conductor 85 through the bank TS—1 of the transfer selector, conductor 130, contacts 131 and 132 of relay 34, in series, conductor 135 and interrupter contacts and motor magnet 33 of the transfer selector to the negative bus 8. The transfer selector will then be operated to the normal position where the circuit is interrupted at the normal contacts of the bank TS—1. Separation of contacts 34' on relay 34 prevents the motor magnet of TS from becoming energized through 1S—1 in case TS reaches the normal position before 1S reaches that position.

45 When switch 2S reaches its normal contact it completes an obvious circuit through its wiper and bank 2S—1 for relay 136 which now becomes energized. Similarly when switches TS, 1S, 3S and 4S reach their normal positions their auxiliary contacts 33', 31', 37' and 84' which are connected in parallel, deenergize relay 113 which returns to its normal position. With relay 113 deenergized and relay 136 energized, the holding circuit for relay 90 is interrupted. Relay 90 in dropping out, by means of its contacts 117, interrupts the circuit of relay 34. Relay 34 then becomes deenergized and by means of its right-hand contact deenergizes relay 100. Thus all of the equipment is now restored to its normal position, which is that shown in the drawing.

55 Should the operator later desire to check the condition of the remote equipment and also the condition of his line conductors, he may do so by again pressing his reset key. If the equipment is in its normal position this operation will produce, in a manner now to be described, a short low pitch tone at the howler 17.

65 As was previously indicated when the equipment returned to its normal position relay 113 became deenergized and relays 136, 118, and 120 became energized. Accordingly, when the operator again presses his reset key and the relays 110 and 50 respond, a circuit will be completed for a short time which extends from the positive bus 7 through the inner left-hand contacts of relay 50, left-hand contacts of relay 113, right-hand contacts of relay 136, conductor 137, contacts of relays 118 and 120 in series, conductor 75, low pitch buzzer 13 and primary winding of transformer 15 to the negative bus. Thus a short low pitch tone will be produced in the howler indicating that the equipment is in the normal condition. This tone will be interrupted when relays 110 and 50 again become deenergized.

70 Let us assume that, with the apparatus in its normal position, one or more of the circuit breakers 1, 2, 3, changes its position either due to accident or to control through some automatic control equipment not indicated in the drawings. When the interlocking switches 9, 10, 11 on any of these apparatus units is operated from one position to the other the holding circuit of the associated indicating relay is momentarily interrupted, and the potential supplied thereto through the interlocking switch is reversed. This interruption and reversal of potential causes the associated indicating relay to drop out and, in dropping out, its right-hand contacts will interrupt its holding circuit, its middle contacts will interrupt the supply of positive potential to one of the contacts in the bank 5S—5, and its left-hand contacts will energize relay 46 all in the manner previously described. Relay 46 will then pick up and supply potential, as before, to the normal contact of the bank 5S—5 and, hence, through conductor 48, contact 49 on the switch 50, and conductor 48' to the motor magnet 52 of the switch 5S. The switch 5S will then operate to the first contact which is connected to an operated indicating relay. Energization of relay 47 will then supply negative potential to the normal contact of the bank 6S—4 and thence, as previously described, establish operation of the relays 68 and 69 in conjunction with the motor magnet 66 to rotate the selector switch 6S, this operation having been previously described. A code will then be transmitted in accordance with the operated apparatus unit. All of the selecting equipment including the apparatus unit selector and position selector will remain in its normal position. It will be noticed that this code indication will be persistently indicated at the dispatcher's station in a tone indicating the position to which the remote unit has operated.

75 The operator having determined from the received indication which of the remote switches operated and the position thereof he may now interrupt the transmission of the code by again pressing his reset key. This operation will as before, provided but one remote apparatus unit operated, reset the operated equipment to the normal position. If, however, two or more remote apparatus units simultaneously changed position, and their corresponding indicating relays became deenergized, it will be apparent that positive potential will have been removed from each of a plurality of contacts in the bank 5S—5, each contact corresponding to the indicating relay associated with an operating apparatus unit. Since operation of the switch 5S is interrupted when the switch reaches the first contact in the bank 5S—5 from which positive potential has been removed, it will be apparent that only the indicating relay associated with these contacts will be restored to its energized condition through 5S—2 when the reset key is pressed. After restoration of this relay it will be seen that the switch 5S will operate to the next contact in the bank 5S—5 from which potential has been removed by the operation of another apparatus unit where its 150

operation will be interrupted. A code will now be transmitted indicating the next apparatus unit which operated in a tone corresponding to the position to which the next unit operated. After 5 a successive operation of the reset key switch 5S will again operate to a further contact from which potential has been removed by operation of an apparatus unit and a corresponding code will be transmitted to the dispatcher's station or if 10 no further apparatus unit has operated then the switches 5S and 6S will return to their normal position and stop, thereby interrupting the code.

It will thus be seen that when the operator receives an indication informing him of the automatic operation of a remote unit, he is not at once informed that more than one unit operated. He may then press his reset key, and if indications cease, he is informed that no further unit has operated, but if a further unit has operated, the 20 code will at once be changed to correspond to the next unit operated, and the tone will change to correspond to the position thereof. Again pressing the reset key will inform the operator of operation of any further apparatus unit.

25 As has been previously stated, equipment constructed in accordance with my invention may be employed to indicate the position occupied by apparatus units having three or more positions as well as those having only two positions, and that 30 with the addition of very little equipment my system may be used for the indication and control of apparatus units, some of which have but two positions and others of which have a large number of positions.

35 It will be recalled that associated with each of the apparatus units 4, 5, having more than two positions, is also an indicating relay 4'', 5'' respectively. Also associated with these apparatus units and common to all of them are a 40 group of relays 140, to 149, the number of these relays employed being dependent upon the maximum number of positions of any of the apparatus units, and each relay corresponding to one position of the different apparatus units. These various apparatus units are provided with a bank of contacts 150, 151 over which they operate in moving through their various positions, the corresponding contacts of which are multiplied together and connected to a corresponding relay 45 in the group 140-149. The arrangement is such that upon deenergization of the indicating relay corresponding to any apparatus unit the relay in the group 140 to 149 corresponding to the position of that unit will be energized thereby causing 50 the code transmitting switch 6S to transmit a code indicating the position of the apparatus unit. The more detailed operation of the equipment in performing the function of indicating the position of apparatus units having three or more 55 positions will now be set forth.

60 Let us assume that the operator desires to ascertain the position of the apparatus unit 4. He will dial the code 2-2-10 thereby operating the switch 1S to its second off-normal contact, 65 switch 2S to its second off-normal contact, and switch 3S to its tenth off-normal contact, transfer switch TS remaining in engagement with its third off-normal contact. The short circuit for the indicating relay 4'' will then be completed from 70 the neutral bus 6 through the left-hand contacts of relay 42, left-hand contacts of relay 39 which is now energized, wiper and second contact of the bank 2S-4, conductor 152, conductor 153, winding of relay 4'' and its right-hand contacts 75 to the neutral bus 6. Relay 4'' is then short

circuited and deenergized and completes a circuit extending from the positive bus through conductor 44, left-hand contacts of relay 4'', apparatus unit 4, which we will say is on its sixth contact, and winding of relay 145 to the negative bus 8. Relay 145 then operates and, by means of its right-hand contacts, closes an obvious circuit for relay 140.

80 At its contacts 154 the relay 4'' closes the circuit for relay 46, and at its contacts 155 it interrupts the supply of positive potential to the ninth contact of the bank 5S-5. Relay 46 then energizes and, as before, through its right-hand contacts energizes relay 42 thereby removing the short circuit from the winding of relay 4''. At its 85 middle contacts it supplies positive potential to the normal contact of the bank 5S-5 which in turn causes energization of the motor magnet 52 and operation of the switch 5S to its ninth contact. When the switch 5S reaches its ninth contact relay 47 becomes energized and supplies negative potential to the normal contact of the bank 6S-4 which in turn starts the cycle of 90 operation of relays 63, 69 and motor magnet 66 which causes rotation of the code transmitting 95 switch 6S.

100 Since relay 140 is now energized, its left-hand contacts permanently interrupt the circuit which, in the case of the operation of the equipment to indicate the position of units having two positions, was intermittently completed between the conductors 77 and 78 in accordance with the code. Accordingly the switch 6S will not now transmit a code in accordance with the position of the switch 5S. Its bank 6S-2, however, will complete the circuit for the code transmitting relay 73 through the right-hand contacts of relay 140 and the left-hand contacts of the relays in the group 140-149 preceding the operated relay which, in the case assumed, is 145. Thus the 110 circuit of code transmitting relay 73 will be completed from the negative bus 8' through conductor 76, winding of relay 73, wiper and normal contact of the bank 6S-2, when the wiper thereof is in its normal position, and right-hand contacts of the relay 140. Similarly, when the wiper 115 6S-2 is on its first contact this circuit will be completed through the left-hand contacts of relay 141 and right-hand contacts of relay 140. When it is on position 2 it will be completed 120 through said contact and the left-hand contacts of relay 142, 141, and the right-hand contacts of relay 140. Similarly the code transmitting relay 73 will be energized when the switch 6S-2 occupies its 2nd, 3rd and fourth positions. In 125 subsequent positions of the switch 6S-2 prior to its tenth contact the circuit of code transmitting relay 73 will be interrupted at the left-hand contacts of relay 145, such that in each of these positions the relay 73 will be deenergized 130 and since relay 14 is now deenergized the circuit of the low pitch buzzer 13 will be completed on each of the six contacts including contacts 5, 6, 7, 8, 9 and 10 of the switch 6S-2 thereby causing the buzzer to transmit six impulses of low pitch 135 informing the operator that the unit 4 is in engagement with its sixth contact. Had unit 4 been in engagement with its eighth contact, relay 143 would have been energized and, accordingly, 8 low pitch impulses would have been transmitted. Similarly had it been on its second contact, relay 149 would have been energized and two low pitch impulses would have been transmitted to the remote station.

140 The operator having determined the position 150

of the selected unit 4 may now change that position by dialing the additional code of three or five impulses. If three impulses are dialed relay 19 will operate to energize relay 4' with current of polarity such that the motor mechanism controlled thereby will operate the unit 4 in one direction, we will say to raise the load on a generator; and if five impulses be dialed relay 19' will respond to reverse the position of relay 4' thereby operating unit 4 in the opposite direction, thereby, as assumed, to lower the load. In this operation the relay 4' may operate as a master relay to control additional relays indicated by the rectangle 4''' for maintaining the energization of the motor during a suitable time interval.

It will be seen that the code transmitted will change directly in accordance with the different positions of the unit. Thus the operator may select a particular generator field rheostat, we will say, or water gate, and then by dialing the position changing codes change the position of the selected rheostat, or gate, back and forth as many times as desired without again operating the apparatus unit selecting equipment, the received code continuously furnishing a positive indication of the change, and extent of change, resulting from each position changing code.

The operator having determined the position of the selected unit and controlled it as desired may now reset the equipment as before by pressing the reset key. The energization of relay 4' during the resetting operation will cause the deenergization of relays 140 and 145.

35 The operator may now, by dialing the code 3-2-9, select and determine the position of the apparatus unit 5 by deenergizing relay 5'' and subsequently control this unit in a manner which will now be understood.

40 When no units having more than two positions are to be supervised the relays 140 to 149 may be omitted the conductor 78 being connected to the positive bus as indicated at 78'.

While I have shown a particular embodiment of my invention, it will of course be understood that I do not wish to be limited thereto since many modifications, both in the circuit arrangement and in the instrumentalities employed, may be made, and I therefore contemplate by the appended claims to cover any such modifications as fall within the true spirit and scope of my invention.

What I claim as new and desire to secure by Letters Patent of the United States, is:

55 1. The combination, in a receiving control system, a plurality of apparatus units, each unit having a plurality of positions, a plurality of selectors including a transfer selector, an apparatus unit selector, and a position selector, said apparatus unit selector including a plurality of selector switches, each selector switch and said transfer selector having an operating magnet, means for supplying a plurality of groups of impulses in code combination to said system and for later supplying an additional group of impulses to said system, means including the transfer selector for supplying each group of impulses of said code combination to an operating magnet of a different selector switch in said apparatus 65 unit selector, whereby a particular apparatus unit is selected, and for connecting the operating magnet of said position selector to respond to said additional group of impulses, and means responsive to the position selector for controlling the position of the selected apparatus unit.

2. In combination, a plurality of devices, each of said devices being capable of assuming different positions, means common to all of said devices for transmitting a code of impulses of current corresponding to each device, remotely controlled selector mechanism for selecting a device for remote control, means controlled by said selector mechanism for causing said transmitting means to transmit a code of impulses of current corresponding to a selected device, without operating said device, means for controlling the character of current comprising the impulses of said code in accordance with the position of the selected device, and means for causing said code of impulses to be transmitted in response to automatic operation of said selected device. 80

3. In combination, a plurality of apparatus units, each of said units being operable to different positions, a normally energized relay associated with each unit, means responsive to the deenergization of any of said relays for repeatedly transmitting a code corresponding to the unit with which the deenergized relay is associated, means for causing deenergization of each of said relays in response to a change in position of the associated unit, and remote control means for effecting the energization of the deenergized relay and for effecting the termination of the transmission of the code corresponding to the unit associated with the deenergized relay. 95

4. In combination, a plurality of apparatus units, each of said units being operable to different positions, a relay associated with each unit, a normally energized locking circuit for each relay, a code transmitter, means responsive to the deenergization of any of said relays for selectively causing said code transmitter repeatedly to transmit a code in accordance with the unit with which the deenergized relay is associated and for selectively preparing a resetting circuit for said relay, 110 remote controlled means for selectively effecting the deenergization of one of said relays to cause the transmission of the code corresponding to the unit with which it is associated and remote controlled means for effecting the completion of said 115 resetting circuit after it has been prepared by said first mentioned means and for terminating the transmission of the code corresponding to the unit associated with the deenergized relay.

5. In combination, a plurality of apparatus units, each of said units being operable to different positions, a relay associated with each unit, position responsive means common to all of said units, a code transmitter, means responsive to operation of any of said relays for selectively causing said transmitter to transmit a code in accordance with the unit with which the operated relay is associated, for selectively preparing a reset circuit for said relay and for selectively connecting said position responsive means to the 130 unit with which said indicating relay is associated, means responsive to said position responsive means for characterizing the code transmitted in accordance with the position of said unit, and means for controlling said relay and said reset 135 circuit from a remote point.

6. In combination, a plurality of apparatus units, each of said units being operable to a plurality of positions, a relay associated with each unit, means for selectively operating said relays 145 from a remote point, means responsive to operation of each of said units for causing operation of the associated relay, means responsive to operation of any of said relays for transmitting a code corresponding to the unit with which the operated 150

5	said mechanism, means controlled by said code selector while it is in a position corresponding to an apparatus unit for transmitting a code of current impulses individual thereto, means for effecting from a remote point the operation of a selected unit as many times as desired to any of its positions while said code selector remains in the position thereof corresponding to the selected unit and means for controlling the character of the impulses of said code in accordance with the position of the unit corresponding to the position of said code selector.	80
10	15. In a supervisory control system, a plurality of apparatus units, each unit being operable to different positions, a code selector common to said units and having a single position corresponding to each unit, means for effecting the automatic operation of any unit from one of its positions to another of its positions, means re-	85
20	sponsive to an automatic operation of a unit for effecting the operation of said code selector to the position thereof corresponding to operated unit, remotely controlled selector mechanism for selecting an apparatus unit for remote control, means controlled by said mechanism for effecting the operation of said code selector to the position thereof corresponding to the unit selected by said mechanism, means controlled by said code selector while it is in a position corresponding to an apparatus unit for transmitting a code of current impulses individual thereto, means for effecting from a remote point the operation of a selected unit without effecting a change in the positions of said mechanism and said code selector and means for varying the character of the impulses of said code in response to a change in the position of the corresponding unit.	90
